[57] CLAIM

The ornamental design for a lock for securing shopping carts when nested together, as shown and described.

DESCRIPTION

FIG. 1 is a top, front, and left side perspective view of a lock for securing shopping carts when nested together showing my new design, the right side being a mirror image of the left;

FIG. 2 is a front elevational view thereof;

FIG. 3 is a rear elevational view thereof;

FIG. 4 is a top plan view thereof;

FIG. 5 is a bottom plan view thereof;

FIG. 6 is a vertical cross-sectional view thereof, taken along line 6—6 of FIG. 2; and,

FIG. 7 is a vertical cross-sectional view thereof, taken along line 7—7 of FIG. 2.

FIG.1
